UNITED STATES PATENT OFFICE.

HENRY G. MILLER, OF CLEVELAND, OHIO.

BOTTLE-RINSER.

No. 806,986.

Specification of Letters Patent.

Patented Dec. 12, 1905.

Application filed March 19, 1904. Serial No. 198,943.

To all whom it may concern:

Be it known that I, HENRY G. MILLER, a citizen of the United States, and a resident of Cleveland, in the county of Cuyahoga and State of Ohio, have invented certain new and useful Improvements in Bottle-Rinsers, of which the following is a specification.

This invention relates to certain improvements in bottle-cleansing machines, and particularly to that class of said devices intended to rinse and brush the bottles after they have been soaked in a suitable alkaline solution and in which the rinsing and brushing means are automatically advanced toward and retracted from the bottles; and the invention consists in certain peculiarities in the construction and arrangement of parts and in certain novel combinations of elements, substantially as hereinafter described, and particularly pointed out in the subjoined claims.

In the accompanying drawings, which illustrate the preferred embodiment of my invention, Figure 1 is a view, partly in side elevation and partly in section, of a device embodying my improvements. Fig. 2 is a top plan view of the bottle-carrying portion of the apparatus. Fig. 3 is a section on the plane of the line 3 3 of Fig. 1. Fig. 4 is a view of a portion of the apparatus, showing a bottle X in place thereon, the revolute tip or wheel being shown in elevation and the other parts in central longitudinal section, the section on which the cap is taken being the line 4 4 of Fig. 6. Fig. 5 is a plan view of the support 30, and Fig. 6 is a horizontal section on the line 6 6 of Fig. 4. Figs. 7 and 8 are detail longitudinal sectional views through one of the tubes 40 and the parts contained therein and connected therewith, (except the rotatable tip, which is shown in elevation,) the line of section of the cap being shown at 7 7, Fig. 6. In Fig. 7 the rinsing-stem is shown at the beginning of its movement into the bottle, and in Fig. 8 said stem is near the end of its movement.

The same reference-numerals designate the same parts in the several figures.

In the present device the means for carrying the bottles preferably comprises a table 21, having its edges formed with a series of openings which form bottle-pockets 20 and provided within said pockets with springs 22 or other suitable devices adapted to clasp the bottles and hold the same firmly in place. Said carrying means also preferably comprises a series of hollow supporting devices

30, arranged in line with said pockets 20 and adapted to engage the necks of the bottles and each having connection with a tube 40, into which the rinsing fluid flows, said tube 60 having means for discharging said fluid against the bottle, which means in the form herein shown consists of a hollow rinsing-stem 31, through which the water flows to the interior of the bottle. Said stem is 65 reciprocatorily mounted, so as to be adapted to be projected into the bottles and retracted from said bottles automatically at predetermined places in the travel of the parts. Said supporting devices are preferably carried by a plate or frame 35. In the construction herein shown the pressure of the rinsing fluid is employed to advance the rinsing-stems 31 and brushes into and retract the same from the bottles, and the 75 means by which this is accomplished comprises a pair of tubes 40 and 50 for each stem 31, each tube serving alternately for the supply and drainage of the fluid. These tubes admit the rinsing fluid alternately at opposite ends of the travel of the respective stems 31, (which latter are provided with heads or pistons 32 or other suitable means to be acted upon by said fluid,) whereby the fluid entering through one will advance said stem 80 and also flow through the stem to the interior of the bottle, and the fluid entering through the other tube will retract said stem. The fluid-discharge stems project into the respective tubes 40, and for this reason the tubes 50 85 open into said tubes 40, suitably above the bottom of the latter. The rinsing fluid is supplied to the tubes through a receptacle or tank 60, the interior of which has communication with a suitable source of supply of fluid 90 under pressure through the supply-pipe 63. The upper wall of this receptacle or tank 60 has passages 62, through which the water is admitted alternately to the interiors of the tubes 40 and 50, and said receptacle or tank 95 100 also has drainage-tubes 61, which when one of said tubes 40 or 50 is in communication with said passage 62, will be in communication with the other of said tubes. The open ends or mouths of said passages 62 and drainage-tubes are closed by a plate or disk 70 when the same are not in communication with said tubes 40 and 50. Said plate 70 is provided with a series of apertures 71, arranged in pairs to receive the ends of the 105 110 pairs of tubes 40 and 50. In order that the supply of rinsing fluid to the tubes may be

automatically controlled, the bottle-carrying portion of the rinser (comprising the tubes 40, plate 70, and bottle-holding devices) and the tank or receptacle 60 are movable relatively to each other. It will be observed that the movement of the movable portion is in a plane parallel with the other portion instead of around or within said other portion. Said plane is preferably horizontal, as shown. It is obviously preferable that the receptacle or tank 60 be stationary and the other parts movable. To this end the table 21, plate or frame 35, and plate 70 are fixed to a rotatable shaft 100, having suitable bearings and provided with a bevel gear-wheel 101, which intermeshes with a suitably-driven bevel-pinion 102, by which said shaft, with the parts attached thereto, is slowly rotated in a horizontal plane.

The operation of the device thus far described is as follows: The attendant stationed at a suitable place fills with bottles to be cleansed the bottle recesses or pockets 20 as they are successively presented to him in the rotation of the table 21. These bottles are inserted neck downward, and their mouths rest upon the respective supports 30. At this place in the rotation of the parts the rinsing-stems 31 and the parts attached thereto are in retracted position. In the rotation of the mechanism from this supply-station the tubes 40 and 50 are brought into communication with the water-inlet passage 62 and drainage-passage 61, respectively, whereby the rinsing fluid enters the bottom of the tube 40 and flows through the rinsing-stem 31 in said tube and into the bottle, said fluid also acting to advance said stem into said bottle, as above explained. In this position of the parts the water drains back through the tube 50 and passage 61. Further rotation of the parts carries said tube 40 out of communication with said supply-passage 62 and into communication with a drainage-passage 61 and also carries the tube 50 into communication with a supply-passage 62, thus causing the water to enter the upper portion of said tube 40 through said tube 50 and to act to retract said rinsing-stem 31, during which movement the drainage is through the lower portion of said tube 40 and the drainage-passage 61. Meanwhile in the movement of the tubes from one passage to another said passages are closed by imperforate portions of the disk or plate 70. The parts are so related that the bottle which has traversed from the supply-station back to said supply-station reaches the latter in a cleansed condition and with the cleansing mechanism retracted therefrom, so that said bottle may be readily removed and its place supplied by another to be cleansed.

It is very advantageous to cause the rinsing fluid to be discharged against the wall of the bottle in a revolving spray, and to this

end there is mounted upon the upper end of each rinsing-stem 31 a cap 80, upon which is rotatably mounted a spirally-grooved revolute tip or wheel 90, the passages of which have communication with the interior of said stem through a series of openings 81 in the top of said cap 80, as shown in Fig. 6, whereby the water flowing through the rinsing-stem will issue from said openings 81 and act upon the vanes 91 (or walls of the spiral grooves) of the wheel, thus rapidly rotating said tip or wheel and causing it to distribute the water in a revolving spray, which dashes against the sides of the bottle. It is also advantageous to provide the device with means for brushing the bottle while the same is being rinsed and to cause said brushing means to rotate in its operation, and to this end a brush 92 is fixed at its lower end to said tip or wheel 90, so as to partake of the movements thereof. This brush preferably comprises a body 93, secured to the upper surface of the tip or wheel by a screw 94 and having flexible wings 95, which are adapted to yield and be moved toward each other in the insertion and removal of the brush through the neck of the bottle and to open out automatically when they pass said neck, so as to engage the surface of the body of the bottle. It is preferably made of rubber.

The advantages of the present device will be readily understood from the above description, and it will be noted that the invention is not restricted to the detail construction herein shown and described, which is merely selected to exemplify what I consider to be the best embodiment of the invention.

Having thus described the invention, what I believe to be new, and desire to secure by Letters Patent, is—

1. A bottle-cleansing mechanism comprising an apertured table for the reception of the bottles and a fluid-supply tank or receptacle movable the one relatively to the other, hollow rinsing-stems, and means controlled by the movement of the movable part for automatically establishing and closing communication of said stems with the fluid-supply tank or receptacle at predetermined places in the travel of said movable part.

2. A bottle-cleansing mechanism comprising an apertured table for the reception of the bottles and a fluid-supply tank or receptacle movable the one relatively to the other, hollow rinsing-stems movable toward and from said table, and means controlled by the relative movement of said table and tank or receptacle for automatically establishing and closing communication of the interiors of said stems with the fluid-supply tank and for advancing and retracting said stems, at predetermined places in the travel of said movable part.

3. A bottle-cleansing mechanism comprising an apertured table for the reception of

the bottles, hollow reciprocatory rinsing-stems, tubes in which said stems are mounted to reciprocate and through which the same are supplied with rinsing fluid, and a receptacle or tank for the rinsing fluid having communication with a source of supply of said fluid under pressure and provided with a passage for the inlet of said fluid to said tubes, said tubes and tank or receptacle being movable the one relatively to the other to automatically establish communication between the same at predetermined places in the movement of the movable part.

4. A bottle-cleansing mechanism comprising an apertured table for the reception of the bottles, hollow reciprocatory rinsing-stems, tubes in which said stems are mounted to reciprocate, each of said tubes having an inlet for the rinsing fluid at its bottom and a separate inlet above its bottom and each tube provided with a tube leading to the upper inlet, a tank or receptacle having communication with a supply of rinsing fluid under pressure and provided with a passage for the inlet of said fluid to said tubes and with a passage for the drainage of said fluid therefrom, said tubes and tank or receptacle being movable the one relatively to the other to throw each tube successively into communication with said supply and drainage passages.

5. A bottle-cleansing mechanism, comprising bottle-holding means and a fluid-supply tank movable the one relatively to the other, hollow rinsing-stems provided with spraying-tips turned by the pressure of rinsing fluid issuing from said stems, and means controlled by the movement of said movable part for automatically establishing and closing communication of said stems with the fluid-supply tank or receptacle at predetermined places in the travel of said movable part.

6. A bottle-cleansing mechanism, comprising bottle-holding means and a fluid-supply tank movable the one relatively to the other, hollow rinsing-stems provided with tips or wheels turned by the pressure of rinsing fluid issuing from said stems, means controlled by the movement of said movable part for automatically establishing and closing communication of said stems with the fluid-supply receptacle at predetermined places in the travel of said movable part, and brushing means secured to said tips or wheels.

7. A bottle-cleansing mechanism, comprising a rotative table having apertures for the reception of the bottles, rinsing-stems movable with said table, a stationary supply means for the rinsing fluid and means movable with said table for automatically establishing and cutting off communication of said stems with said supply means at predetermined places in the travel of the parts.

8. A bottle-cleansing mechanism, comprising

ing a rotative table having apertures for the reception of the bottles, rinsing-stems movable with said table and also movable toward and from the same, a stationary supply means for the rinsing fluid and means movable with said table for automatically establishing and cutting off communication of said stems with said supply means at predetermined places in the travel of the parts.

9. A bottle-cleansing mechanism, comprising a rotative table having apertures for the reception of the bottles, tubes movable with said table, rinsing-stems reciprocatorily mounted in said tubes, a stationary supply means for the rinsing fluid, having a passage through which it communicates with said tube and means for closing said passage at predetermined places in the travel of the parts.

10. A bottle-cleansing mechanism, comprising a rotative table having apertures for the reception of the bottles, a plurality of tubes movable with said table, rinsing-stems reciprocatorily mounted in said tubes, a tube connected with each of the first-mentioned tubes above the bottom of the same, a stationary supply means for the rinsing fluid having supply and drainage passages with which each of said tubes alternately communicates, and means for closing said passages when said tubes are not in communication therewith.

11. A bottle-cleansing mechanism, comprising a rotative table having apertures to receive the bottles, a plate or frame rotative with said table and provided with supports to engage the bottle-necks, tubes projecting therefrom, rinsing-stems reciprocatorily mounted in said tubes, an apertured plate or disk arranged at the lower ends of said tubes and mounted to rotate therewith, and a stationary supply means for the rinsing fluid having a passage to communicate with said tubes.

12. A bottle-cleansing mechanism, comprising a rotative table having apertures to receive the bottles, a plate or frame rotative with said table and provided with supports to engage the bottle-necks, a plate or disk also partaking of the rotative movement imparted to said table and plate or frame, a series of pairs of tubes arranged between said plates and carried thereby, one tube of each of said pairs opening into the other tube thereof above the bottom of the same, a reciprocatorily rinsing-stem in one tube of each of said pairs, and a stationary supply means for the rinsing fluid having supply and drainage passages with which said tubes alternately communicate at predetermined places in the travel of the parts.

13. A bottle-cleansing means, comprising a bottle-holding device, a rinsing-stem provided with a revolvably-mounted spraying-tip having spirally-arranged passages, and means

through which the rinsing fluid is supplied to said tip.

14. A bottle-cleansing means, comprising a bottle-holding device, a rinsing-stem having a cap provided with exit-apertures, a spraying-tip revolubly mounted on said cap and having spirally-arranged passages, and means through which the rinsing fluid is supplied to said stem.
15. A bottle-cleansing means, comprising a rinsing-stem provided with a spraying tip or wheel revolubly mounted thereon, brushing means secured to said tip or wheel, and means by which said tip or wheel is revolved by the pressure of the rinsing fluid.

16. A bottle-cleansing means, comprising a rinsing-stem having a cap provided with exit-apertures, a spraying tip or wheel revolubly mounted on said cap and having spirally-arranged passages or vanes, brushing means secured to said tip or wheel, and means for supplying the rinsing fluid to said stem.

17. A bottle-cleansing means, comprising a reciprocating rinsing-stem having a revoluble spraying tip or wheel and means by which the pressure of the rinsing fluid reciprocates said stem and turns said tip or wheel.

18. A bottle-cleansing means, comprising a reciprocating rinsing-stem having a revoluble spraying tip or wheel provided with a brushing means partaking of the movements thereof, and means by which the pressure of the rinsing fluid reciprocates said stem and turns said wheel.

19. A bottle-cleansing means, comprising a rinsing-stem, a revoluble brushing means connected therewith, and means operated by the pressure of the rinsing fluid for turning the brush relatively to said stem.

20. A bottle-cleansing means, comprising a rinsing-stem, a revoluble brushing means connected therewith and comprising a body having flexible brushing members, and means operated by the pressure of the rinsing fluid for turning the brush relatively to said stem.

21. A bottle-cleansing means, comprising a reciprocating rinsing-stem, a revoluble brushing means connected therewith, and means whereby the rinsing fluid reciprocates said stem and turns said brushing means.

22. A bottle-cleansing means, comprising a reciprocating rinsing-stem having a cap provided with exit-apertures, a spraying tip or wheel carried by said stem and revolubly mounted on said cap, means by which said tip or wheel is turned by the pressure of the rinsing fluid issuing from said stem, brushing means secured to said tip or wheel and partaking of the movements thereof, said brushing means comprising a body having flexible

brushing members, means for holding the bottles, and means for automatically admitting the rinsing fluid to said stems and for causing the same to reciprocate at predetermined times.

23. A bottle-cleansing mechanism comprising a shaft, means for rotating the same, a table carried by said shaft and having recesses in its edge to receive the bottles, spring clamping means in said recesses, and means for automatically supplying rinsing fluid to the interiors of the bottles at predetermined places in the travel thereof with said table.

24. A bottle-rinser, comprising a bottle-carrying portion and a fluid-supply tank or receptacle having an aperture for the egress of the fluid, said parts being relatively movable in parallel planes, and said bottle-carrying portion comprising a bottle-holder, a tube having means for discharging the rinsing fluid against the bottle and a plate through which the supply of fluid to said tube is controlled, said plate having an aperture and a solid portion which alternately register with the aperture in said tank or receptacle.

25. A bottle-rinser, comprising a bottle-carrying portion and a fluid-supply tank or receptacle having an aperture for the egress of the fluid, said parts being relatively movable in parallel planes, and said bottle-carrying portion comprising a bottle-holder, a tube having means for discharging the rinsing fluid against the bottle and means for automatically establishing and closing communication of the interior of said tube with the interior of said tank or receptacle at predetermined place in the movement of the movable part.

26. A bottle-rinser, comprising a bottle-carrying portion and a fluid-supply tank or receptacle, said parts being relatively movable in parallel planes, and said bottle-carrying portion comprising a bottle-holder, a tube provided with a reciprocating rinsing-stem, having a head, and means for automatically establishing and closing communication of the interior of said tube, alternately at opposite sides of said head, with the interior of said tank or receptacle at predetermined places in the movement of said movable part.

Witness my hand, this 28th day of February, 1904, at the city of Cleveland, in the county of Cuyahoga and State of Ohio.
